UNITED STATES PATENT OFFICE.

LOUIS SANDERS, OF NEW YORK, N. Y.

DESIGN FOR A LEATHER CHATELAINE-BAG.

SPECIFICATION forming part of Design No. 34,066, dated February 12, 1901.

Application filed December 18, 1900. Serial No. 40,319. Term of patent 3½ years.

To all whom it may concern.

Be it known that I, LOUIS SANDERS, a citizen of the United States, and a resident of the city of New York, borough of Brooklyn, in the 5 county of Kings and State of New York, have invented and produced a new and original Design for a Leather Chatelaine-Bag, of which the following is a specification, reference being had to the accompanying drawings, forming a part of thereof, in which—

Figure 1 is a perspective view of a chatelaine-bag embodying the features of my design, and Fig. 2 is a side elevation of the bag.

The design consists in the circular formation of the side faces A of the bag, the semi-circular gusset B at the bottom and lower side portions of the bag, the welts C for the gus-

set at its junction with the side faces, the semicircular frame D at the upper portion of the bag, and the inclined surfaces E where 20 the ends of the gusset meet the frame.

Having thus described my invention, I claim as new and desire to secure by Letters Patent—

The design for a leather chatelaine-bag 25 herein shown and described.

In testimony whereof I have signed my name to this specification in the presence of two subscribing witnesses.

LOUIS SANDERS.
